UNITED STATES PATENT OFFICE

EDWARD E. KLEINSCHMIDT, OF PARK RIDGE, ILLINOIS, ASSIGNOR TO TELETYPE CORPORATION, OF CHICAGO, ILLINOIS

PRINTING TELEGRAPH

Application filed February 23, 1927, Serial No. 170,283. Renewed September 17, 1929.

The present invention relates to selecting and printing mechanisms, and more particularly the invention relates to printing telegraph mechanisms. The present application is a continuation in part of application Serial No. 726,859, filed July 18, 1924.

A primary object of the invention is to provide novel single magnet selector mechanisms in which point selection and a maximum margin of operation of the mechanism is secured.

Another object of the invention is to provide a novel simplified selecting mechanism for type wheel printers, especially adapted for use as a stock ticker and adaptable for high speed operation.

A further object of the invention is to provide novel single magnet selecting and printing mechanisms especially adapted for stock ticker, fire alarm, police, and similar signalling.

Further objects of the invention are such as may be attained by a utilization of the various combinations, subcombinations and principles hereinafter set forth and as are defined by the scope of the appended claims.

As shown in the drawings—

Figure 1 is a plan view with parts removed showing a preferred embodiment of my invention.

Figure 2 is a side elevation with parts broken away of the form of invention shown in Figure 1.

Figure 3 is a side elevation partially in section of the form of invention shown in Figure 1.

Referring to Figure 1, the mechanism is controlled by a single selector magnet which may be of any well known construction.

As shown, the selector magnet is of a sensitive polarized type especially designed for use in stock ticker operation, and comprises a permanent U-shaped magnet 1, to one pole of which the laminated soft iron core 2 is secured. Disposed on core 2 are the magnet windings 3. Pivottally supported from the other pole of the permanent magnet 1 by means of pin 4 is the oscillating armature 5, the motion of which is limited by means of the adjustable stop screws 6. Riveted to the

armature 5 is the bifurcated actuating extension 7, the bifurcated end of which fits into annular channel 8 of the selector cam shaft extension 9. The cam shaft extension 9 is formed integrally with the shaft 10 and is slidably journaled in a stationary bearing 11 which is supported from a frame work (not shown) in any suitable manner. Formed integrally with the opposite end of cam shaft 10 is a bearing extension 12 which fits slidably into a suitable recess or bore formed in the end of the shaft section 13. Drive shaft section 13 is journaled for rotation in fixed bearing 14 and rigidly secured thereto and driven thereby is trip cam 15 which is provided with a driving extension 16. Driving extension 16 projects into a suitable slot formed in cam shaft drive member 18 which is pivotally secured to cam shaft 10 by means of securing pin 19. Secured to 70 and driving the shaft section 13 is a friction or slip clutch 20 which may be of any suitable construction and which is driven by shaft section 21. Shaft section 21 is journaled in fixed bearing 22 supported from the framework and is driven by spiral gear 23 mounted thereon. Gear 23 meshes with and is driven by a spiral pinion 24 which is mounted on the shaft 25. Shaft 25 in operation is continuously rotated at a predetermined and constant speed by an electric motor or in any other suitable manner.

Secured in cam shaft 10 is a stop pin 26 which in the position of parts shown in Figure 1, engages a stationary stop projection 27, 85 suitably supported from the frame work of the mechanism. Spaced spirally around shaft 10 and rigidly secured thereto are the selecting cams or pins 28 to 33 (Figures 1 and 3). In the position of parts shown in Figure 1, as cam shaft 10 rotates cams 28 to 33 will successively engage the inclined ends 34 of point selection levers 35 which are pivotally mounted on the stationary supporting rod 36, depressing the forward ends of the levers 90 against the tension of helical springs 38. A spring 38 is provided for each lever 35, the upper ends thereof being secured to the rearward extensions of levers 35, and the lower ends thereof being secured to the supporting 95

100

framework. Springs 38 normally hold the extensions of levers 35 in engagement with stationary stop bar 39 carried by the framework. With the selector magnet energized to tilt armature 5 in the opposite direction about the pivot 4, cams 28 to 33 will be shifted to pass between levers 35 as the cam shaft rotates, and will engage and ride over cam surfaces 40 of selector setting arms 41. Arms 41 are also pivotally supported from stationary rod 36 and are spaced from the levers 35 by suitable spacing collars. Formed on each arm 41 is a latching extension 42 adapted to hook under latching shoulder 43 of latch members 44 individual thereto when arms 41 are depressed. Latches 44 are pivotally supported from the frame of the mechanism by pins 45 (Figure 3) and are provided with the actuating extensions 46 positioned in alignment with levers 35 and adapted to be actuated by cam pins 28 to 33, as will more fully hereinafter appear. Disposed between extensions 47 of latch members 44 and extensions 48 of the selector arms 41 are the helical springs 49 which normally urge the latches 44 counter-clockwise and the selector arms clockwise in Figure 3.

Arms 41 are guided for movement in slots formed in comb member 50 supported from the frame. At their forward ends arms 41 are slotted to slidably receive the ends of the actuating extensions 51 of selector disk setting forks 52. Forks 52 are pivotally supported from supporting rod 53 and are each provided with a pair of cam supporting tines 54 and 55. Tines 54 extend upward and have formed at their outer ends cam surfaces 56 which are adapted to engage the shifting cam projections 57 of permutation or selector disks 58 to 62 when the tines are raised, while tines 55 extend downward and have formed at their outer ends cam surfaces 63 engaged by cam projections 64 of the disks 58 to 62, as will more fully hereinafter appear.

Selector disks 58 to 62 are provided with the central spacing and supporting bosses 63' provided with central openings by means of which the disks are slidably mounted on the square sleeve 64' mounted on a square section 50 of the type wheel shaft 65. Formed in the periphery of the disks 58 to 62 are V-shaped selector notches 66. Notches 66 are variably spaced on disks 58 to 62 in a manner and for a purpose that will more fully hereinafter appear. Seeker member 67, provided with a pair of spaced feelers 68 and 69 individual to each selector disk 58 to 62, is pivotally supported from the frame work by pin or rod 70. In marking position of disks 58 to 62 on shaft 65 feelers 68 individual thereto will be in engagement with the periphery thereof, and in spacing position of the disks feelers 69 individual thereto will engage the periphery thereof.

Formed integrally with the seeker 67 is

an extension 71 provided with ears 72 to which the upper ends of printing hammer latches 73 and 74 are pivotally secured by means of screws 75. Formed integrally on latches 73 and 74 are projections 76 and 77 respectively which in operation are adapted to engage the ends of tines 78 and 79 of hammer control fork 80 pivotally supported on pin 53. Fork 80 is provided with an actuating extension 81 which fits into a slot formed in the end of the selector arm 41 controlled by cam pin 33 of cam shaft 10. Coil spring 82 wound around seeker supporting pin 70 with the ends thereof in engagement with the seeker and a pin 83 suitably secured to the frame urges seeker 71 together with the parts carried thereby in a clock-wise direction in Figure 2 about the pivot pin 70 forcing feelers 68 and 69 into engagement with disks 58 to 62. Helical springs 83' secured at one end to the lower ends of latches 73 and 74 respectively and at their other ends to the frame work, force latches 73 and 74 counter-clockwise about their pivots 75 and hold latching shoulders 84 thereof in engagement with the free ends of a pair of printing hammer arms 85. Hammer arms 85 are pivotally mounted on stationary rod 86 and are urged in a clockwise direction in Figure 2 by helical springs 87. A pair of adjustable stop screws 88 supported from the frame of the mechanism limit the movement of arms 85. Each arm is provided with a striking hammer and tape supporting section 89 over which tape 90 adapted to receive printed impressions is disposed. Positioned above the hammer sections 89 of arms 85 are the rows of letter and figure characters 92 and 91 respectively, of type wheel 93. Type wheel 93 is rigidly secured to and rotatable with type wheel shaft 65 by means of the securing nut 94. A suitable inking device such as an ink roller or ink ribbon (not shown) is utilized to effect proper inking of the type for the printing operation.

Secured to and rotatable with type wheel shaft 65 is a spacing and hammer restoring cam 96 (Figures 1 and 2) provided with an actuating notch 97 in its periphery. A cam roller 98 carried on the end of arm 99 of a restoring and spacing bell crank member 100 normally rides against the periphery of the cam 96. Member 100 is pivotally mounted on a spindle or shaft 101 and is positioned between the printing hammers 85. Secured to the arm 102 of the member 100 is a restoring pin 103 which is adapted to engage restoring extensions 104 of printing hammers 85, as will more fully hereinafter appear. Pivotally supported from arm 106 of member 100 by means of pin 107 is a spacing pawl 108. A spring 109 secured at one end to the frame of the mechanism by means of pin 110 and at its opposite end to pin 111 of the pawl 108, normally urges the nose of pawl 108 into

engagement with spacing ratchet wheel 112 and at the same time forces the member 100 counter-clockwise about its pivot, holding actuating roller 98 in engagement with the 5 periphery of cam 96. Ratchet 112 is rigidly secured to and drives a spacing roller 113 which is rotatably supported on the spindle 101. Tape 90 passes over the roller 113 and is held in engagement therewith by roller 10 114 which is rotatably supported on the upper end of arm 115. Arm 115 is pivotally supported from the framework by pin 116, and is urged by spring 117 into engagement with tape 90 pressing the tape against roller 15 113.

Type wheel shaft 65 is supported from the framework in bearings 118 and slidably keyed thereto is toothed drive clutch member 119. Clutch member 119 is provided with a cam 20 surface 120 and stop projection 121 adapted to engage the end of stop arm 122 of trip member 123 which is pivotally mounted on the rod 53. Spring 123' secured at one end to the trip member 123 and at its other end 25 to the framework, normally urges arm 122 downward, holding it in engagement with the clutch member 119, and urges trip arm 124 of member 123 upward so that its end is positioned in the path of trip cam 15. Helical spring 125 interposed between a shoulder on the shaft 65 and the end of the clutch member 119, normally urges the clutch member 30 towards cooperating toothed clutch member 126 so that when arm 122 is raised the clutch 35 members will be forced into engagement. Clutch member 126 is formed integrally with a spiral gear 127 which is journaled on the end of shaft 65 and meshes with and is driven by spiral pinion 24.

40

Operation

In operation, shaft 25 and pinion 24 rotate continuously, driving gears 23 and 127 continuously in opposite directions. When 45 no signals are being received, the position of parts will be as shown in Figure 1, with the stop pin 26 of cam shaft 10 engaging the fixed stop 27 and clutch member 119 held out of engagement with the clutch member 50 126 by the stop arm 122, and shafts 10 and 65 126 will be at rest. The signals to which the mechanism is responsive each comprise a start condition, a code combination of selecting conditions and a stop condition. A stop 55 condition is normally on the line holding the parts in the position shown in Figure 1. Core 2 and armature 5 of the selector magnet are magnetized by permanent magnet 1. When a start condition is received 60 65 the polarity of the current flowing through windings 3 is reversed, decreasing the magnetic field strength of the outer leg of core 2 and increasing the magnetic field strength of the inner leg of the core 2 causing armature 5 to tilt in the opposite direction. It

will accordingly be seen that a sensitive selector magnet in which springs are eliminated especially adapted for stock ticker work is provided. Tilting of armature 5 in response to the start condition shifts cam shaft 10 endwise so that stop pin 26 will be disengaged from the stop shelf 27. As soon as pin 26 is free from the shelf 27 friction clutch 20 will become effective to drive cam shaft 10 at a speed which is definitely timed with relation to the incoming impulses. With the arrangement shown, the first impulse of the signal following the start impulse is received just before pin 28 passes the extension 46 of the latch 44 controlled thereby. 70

If this impulse is a spacing impulse, armature 5 will be actuated to position the cam pin 28 to engage the extension 46 of the latch individual thereto, rocking the latch about its pivot 45 in a clockwise direction 80 in Figure 3. If selector arm 41 individual to pin 28 had been latched downward in the preceding selection, actuation of latch 44 individual thereto will free the depressed arm which will move to its upper position under the influence of spring 49 individual thereto. If selector arm 41 individual to pin 28 had not been depressed on the preceding selection by the cam pin 28, then actuation of the latch 44 will produce no effect on its position and the arm will remain in its upper or unactuated position. Immediately after the cam pin 28 actuates latch 44, pin 28 will pass alongside projection 40 of the selector arm 41 individual to the pin 28 and will ride over cam surface 34 of the point selection lever 35 controlled thereby, depressing the lever. Until the pin 28 has passed the projection 40 of the selector arm 41 individual thereto, cam shaft 10 will be prevented from endwise movement so that the condition of energization of the coil 3 can not affect the position of the cam shaft during this interval and the cam shaft is locked against movement during this interval. If 105 the impulse immediately following the start impulse is a selecting condition, the selector magnet will be operated to position the pin 28 so that it will pass alongside latch 44 and lever 35 individual thereto, and will ride over the cam surface 40 of the selector arm 41 controlled thereby, depressing its selector arm 41. As soon as arm 41 is depressed, pin 28 will pass alongside cam projection 34 110 of arm 35 individual thereto and the position of shaft 10 cannot be changed by the selector magnet until the selector arm 41 has been completely depressed and pin 28 has passed the projection of the arm 35. 115 When the selector arm 41 is depressed, spring 49 will force the shoulder 43 of the latch 44 individual thereto over the locking projection 42 of the arm, locking the arm in its lower or selected position. In similar manner the cam pins 29 to 33 will be positioned in align- 120

125

ment with the projections 46 of the latches 44, and the surfaces 34 of the levers 35, or in alignment with the selecting arms 41 individual thereto, depending upon whether the 5 succeeding received impulses are spacing or marking conditions, causing the selector arms 41 to be positioned into upper or lower position in accordance with the received combination of character selecting impulses. After 10 a setting operation has been initiated by any of the selecting cam pins 29 to 33, the cam shaft will be locked against movement until the setting operation has been completed. The locking of the cam shaft is an important feature of my invention and is applicable to any selector mechanism embodying an axially movable rotary cam shaft for setting the selector members. For example, 15 by adding the levers 35 between selecting fingers shown in copending application S. N. 704,022, the locking action of the cam shaft during setting operation may be secured.

After the selecting last impulse has been received and the setting of the selector members controlled by the pins 33 has been initiated, a stop condition is placed on the line and a projection on trip cam 15 rocks the arm 124 of the trip control member 123 downward causing arm 122 to be raised upward and out of engagement with cam surface 120 and stop projection 121 of the clutch member 119. This frees the clutch member 119 for movement under influence of spring 125, into engagement with clutch member 126 and a driving connection is established between gear 127 and type wheel shaft 65 starting shaft 65 together with the parts carried thereby into rotation in a clockwise direction in Figures 2 and 3.

40 The setting of selector arms 41 in their upper or lower positions in accordance with the received code combinations shifts the selecting forks 52 and 80 positioning setting cams 56 or 63 as the case may be, in the path of 45 rotation of the cam projections 57 and 64 respectively of the selector disks 58 to 62, and the tines 78 and 79 in front of projection 76 or 77 of latches 73 or 74. As disks 58 to 62 rotate with the shaft 65, cam projections 56 or 63 will engage and ride over cams 57 or 64 depending upon whether the control forks 52 individual thereto are in lowered or raised position. As projections 57 and 64 ride over cams 56 and 63, disks 58 to 62 are shifted 50 axially on shaft 65 into alignment with one or the other of the spaced seekers 69 or 68 of seeker 67 individual thereto. The setting of disks 58 to 62 axially on shaft 65 occurs simultaneously at the beginning of the revolution of shaft 65 and during the reception of 55 the stop condition following the selecting conditions of the received signal. The stop condition tilts armature 5 of the selector magnet to the position shown in Figure 1, stop 60 pin 26 engages stop shelf 27 and shaft 10 is 65

brought to rest, completing its cycle of operation, and a succeeding code combination may be received and set up successively on selector arms 41.

After the disks 58 to 62 have been shifted 70 axially in accordance with the received code combinations, continued rotation of shaft 65 will bring a notch 66 beneath each of the feelers 68 and 69 in engagement with the disks, permitting the seeker 71 to rotate clockwise in Figure 2, under the influence of 75 spring 82. With hammer control fork 80 in the full line position shown in Figure 2, as seeker 71 moves inward, projection 77 of latch 74 will engage the end of tine 79 of fork 80 and the lower end of latch 74 will shift outward against the tension of its spring 83 disengaging the shoulder 84 from the ends of the inner printing hammer controlled thereby. This movement of latch 74 releases the 80 inner hammer 85 for a printing stroke under the influence of its spring 87 and a selected letter will be printed. When fork 80 is set 85 in its upper position as indicated by the dotted lines in Figure 2, projection 76 of the printer control arm 73 will engage the end of tine 78 of fork 80 and the outer printing hammer 85 will be released for a printing stroke under the influence of its spring 87 to print 90 a figure. It will be understood that notches 95 66 in selector disks 58 to 62 are arranged so that for each combination of positions or setting of the disks a different pair of characters on the type wheel will be positioned over the hammer sections 89 of printing hammers so that for each different setting of the disks 58 to 62 a different pair of characters will be in the printing position, only one of the hammer arms 85 being released to print a letter or 100 figure, depending upon the position of the fork 80. The parts are so adjusted that the released printing hammer engages the end of its stop screw 88 with a blow just before the hammer section 89 impacts the tape 90 against the selected character, and the remainder of a printing stroke of the hammer section 89 is completed due to the resilience 105 of the hammer member 85. In this way a spring printing action is secured while the type wheel is rotating and immediately after the impact the hammer section rebounds out of contact with the type wheel before the released hammer is restored.

110 After feelers 68 and 69 have dropped into the selecting notches releasing the proper printing hammer, continued rotation of the disks 58 and 62 will cam the feeler 71 outward, and just before the completion of a revolution of shaft 65, roller 98 of printing hammer restoring member 100 will drop into 115 notch 97 of cam 96 rocking the restoring pin 103 and advancing oscillating spacing pawl 108 over one tooth of ratchet 112. Pin 103 120 engages projection 104 of the release printing hammer, restoring the hammer counter- 125 130

clockwise about the pivot 86 until shoulder 84 of latch 73 or 74, as the case may be, rides over the end of the released hammer restoring the parts in the position shown in Figure 2. 5 As the roller 98 passes out of notch 97 pawl 108 is actuated to rotate ratchet 113, roller 112, and tape 90 through a letter space, and cam surface 120 of the clutch member 119 will engage the end of stop arm 122 forcing 10 clutch member 119 out of engagement with clutch member 126 and breaking the driving connection for shaft 65. Shaft 65 will then come to rest with the stop projection 121 of clutch member 119 engaging the end of stop 15 arm 122 as shown in Figure 1, completing the printing cycle. Immediately after the printing operation, selector arm 41 controlling hammer control fork 80 may be reset in accordance with the last selecting impulse of 20 the succeeding code combination and as soon as shaft 65 comes to rest at the end of a complete revolution it may again be immediately tripped to transfer the succeeding selection to the disks 58 to 62. In this way a complete 25 overlap in the setting of the selectors and the cycle of printing operations may be secured.

It will be apparent to those skilled in the art that instead of shifting selector members 30 axially, selector members 41 may be utilized to rotate notched permutation disks slightly to selectively align notches or holes contained therein, or may be utilized to selectively shift notched permutation bars in well known 35 types of selecting mechanisms. Also instead of providing a pair of printing hammers to print the characters in the different cases, a single printing hammer with a shift mechanism may be provided. Other variations of 40 my invention and uses for the subcombinations of mechanisms described will be apparent to those skilled in the art and may be made without departing from the spirit of my invention. Accordingly, what is desired 45 to be secured by Letters Patent and claimed as new is:

1. In a printing telegraph receiver, a selector device operatively responsive to received line current impulses and means following each operation of said selector device in response to a line current impulse for rendering it unresponsive to further impulses for a predetermined interval.

2. In a printing telegraph receiver, a selector device operatively responsive to received line current impulses and means following the beginning of each operation of said device for locking said device to complete its operation.

3. In a printing telegraph receiver, a selector device, means for moving said selector device to either of two positions in response to received line current impulses and means operative following the start of each operation of said device for locking it in its as-

sumed position for a predetermined length of time.

4. In a printing telegraph receiver, a plurality of cam members, a selector member and latch member individual to each of said cam members, means whereby said cam members operate said selector members in response to received impulses, said selector members being arranged to lock said cam members from further operation responsive to a succeeding impulse. 70 75

5. In a printing telegraph receiver, a plurality of cam members, a plurality of latch members and selecting members individual to said cam members and arranged to be operated successively by their associated cam members and means following each operation whereby said selector members or latch members lock their individual cam members from further operation. 80 85

6. In a printing telegraph receiver, a plurality of cam members, a selector member and latch member individual to each of said cam members, means responsive to line current impulses whereby said cam members selectively operate said selector members, said latch members being arranged to lock said cam members from further selective operation following each of said operations. 90 95

7. In a printing telegraph receiver, a plurality of selector members, a plurality of latch members individual to said selector members, and means operating in accordance with received line current impulses for operating either said latch members or said selector members. 100

8. In a printing telegraph receiver, a plurality of selector members, each of said selector members having a normal and an operate position, means whereby said selector members are either moved to their operate position or remain in their normal position in accordance with received impulses, latching devices individual to each of said selecting members for latching said members in their operate position and means responsive to impulses of a predetermined character for operating said latch members to restore said selector members. 110 105

9. In a printing telegraph receiver, a plurality of selector members, a latch member individual to each of said selector members, each of said latch members having an extension for latching its associated selector member when the selector member is moved to an operate position, and means for either moving said selector members to their operate position or operating said latch members in accordance with the received line current impulses. 115 120 125

10. In a printing telegraph receiver, a plurality of selector members, means for selectively operating said selector members, means operative following each selection for latching said selective members, said means com- 130

prising latching members tensionally connected to said selector members.

11. In a printing telegraph receiver, a plurality of selector members, a latch member individual to each of said selector members, means for selectively operating said selectors, and means including a spring connecting each of said latch members with its individual selector member for moving said latch members to latch said selector in its operated position.

12. In a printing telegraph receiver, a plurality of selector members, a plurality of latch members, a rotating shaft operable axially in response to received line current impulses for operating either said selector or its associated latch member.

13. In a printing telegraph receiver, a plurality of selector members, a plurality of latch members, and a rotating shaft, said shaft being movable longitudinally in response to received impulses, a plurality of cam members integral with said shaft and arranged about its periphery for selectively operating said selector members or said latch members in accordance with its position of said shaft.

14. In a printing telegraph receiver, a plurality of selector members, a plurality of latch members, a rotating shaft comprising a plurality of cam members individual to said selector members, said selector members and said latch members being longitudinally spaced from each other with respect to said shaft, means responsive to line current impulses for moving said shaft longitudinally and cam members integral with said shaft and individual to said selector members for operating said selector members or said latch members in accordance with the longitudinal movement of said shaft.

15. In a printing telegraph receiver, a plurality of selector members, a plurality of latch members individual to said selector members, a rotating shaft, said selector and latch members being arranged longitudinally from each other with respect to said shaft, a plurality of point selectors, a plurality of cam members integral with said shaft, means responsive to line current impulses for moving said shaft longitudinally, said cam members being arranged on said shaft to operate either said selector members or said latch members in accordance with the movement of said shaft, and arranged to thereafter be positioned either opposite said selector member or said point selector whereby said shaft is locked against longitudinal movement during this period of time.

16. In a printing telegraph receiver, a plurality of selector members, a plurality of latch members individual to said selector members, a rotating shaft, a plurality of cam members integral with said shaft and individual to said selector members, means responsive to line current members for moving

said shaft longitudinally, said cam members being positioned for operating their individual selectors or latch members as said shaft is operated by said impulses, and a plurality of selector members positioned to lock said shaft from longitudinal movement following each operation.

17. In a printing telegraph receiver, a plurality of selector members, a plurality of latch members individual to said selector members, a rotating shaft comprising a plurality of cam members, said cam members being arranged to be sequentially positioned opposite their individual selectors and latch members, means responsive to received impulses for operating said shaft longitudinally whereby said cam members operate said selectors or said latch members in accordance with the impulses.

18. In a printing telegraph receiver, a plurality of selector members, a plurality of latch members individual to said selector members, a rotating shaft comprising a plurality of cam members, said cam members being arranged to be sequentially positioned opposite their individual selectors and latch members, means responsive to received impulses for operating said shaft longitudinally whereby said cam members operate said selectors or said latch members in accordance with the impulses, and a plurality of point selectors individual to said latch selector members positioned to latch each of said cam members following its operation on the associated selector member against operation in response to received impulses.

19. In a printing telegraph receiver, a plurality of selector members, a plurality of point selectors individual to said selector members and positioned adjacent thereto, a rotating shaft comprising a plurality of cam members positioned about said shaft, said selector members or point selectors being periodically in the path of their individual cam members whereby said cam members are locked from further operation.

20. In a printing telegraph receiver, a rotating shaft, a plurality of cam members integral with and positioned about said shaft, means for operating said shaft longitudinally in response to received impulses and means co-acting with said cam members for preventing longitudinal movement of said shaft.

21. In a printing telegraph receiver, a rotating shaft, a plurality of cam members integral with and positioned about said shaft, means for operating said shaft longitudinally in response to received impulses and means co-acting with said cam members for locking said shaft from longitudinal movement.

22. In a printing telegraph receiver, a plurality of selector members, a latch member individual to each of said selector members and a point selector member individual to each of said selector members, a rotating

shaft, a plurality of cam members arranged about said shaft, means for moving said shaft longitudinally in response to received impulses, said selector members being arranged to be operated by their individual cam members in accordance with the longitudinal movement of said shaft, said selector member and said individual point selector member being arranged to lock their individual cam members in accordance with the operation of said cam.

23. In a printing telegraph receiver, a plurality of selector members, each of said selector members having a normal operate position, a plurality of latch members individual to each of said selectors and provided with notches for latching their selector members in operating position and operating members for operating the selector members to their operating position or the latch members to unlatch its associated selector member in accordance with received impulses.

24. In a printing telegraph receiver, a plurality of selector members, a plurality of latch members individual to their selector members, and operative means responsive to received current for selectively operating either the selector members or their individual latch members in accordance with received impulses.

25. In a printing telegraph receiver, a plurality of selector members, a plurality of latch members, a rotating shaft comprising a plurality of cam members one for each of said selector members, means responsive to impulses of a predetermined character for moving said shaft longitudinally whereby said cam members operate their individual selector members and means responsive to impulses of a different character for longitudinally restoring said shaft to its original position whereby said cam members operate their individual latch members.

26. In a printing telegraph receiver, a plurality of selector members, a rotating shaft, a plurality of cam members individual to said selector members integral with and positioned around said shaft, said shaft being rotatable for sequentially positioning each of said cam members adjacent to its associated selector member, and means for latching said selector members in position until released by a change of impulses in the succeeding cycle of operations.

27. In a receiver device, a plurality of selector disks, a plurality of type characters, means responsive to received impulses for moving said disks longitudinally and means responsive to a predetermined setting of said disks for selectively operating one of said type characters.

28. In a receiver device, a shaft, a plurality of disks secured to said shaft, a plurality of selector disks, each of said disks having two

positions longitudinally along said shaft, means responsive to predetermined combinations of impulses for selectively setting said disk members, a plurality of type characters and means responsive to the positioning of said disk members for selectively operating one of said type characters.

29. In a receiver device, a plurality of selector disks, a type wheel, a shaft for supporting said disks and said type wheel, means responsive to predetermined combinations of impulses for selectively positioning said disks longitudinally along said shaft, means for rotating said shaft, and means for selecting a position in the rotation of said shaft in accordance with the longitudinal positioning of said disks.

30. In a receiver device, a plurality of notched disk members, a type wheel, a shaft for supporting said notched disks and said type wheel, said shaft normally rotating, means for sliding said disk members longitudinally along said shaft, in response to received current impulses, a normally non-operating printing hammer and means responsive to a predetermined setting of said disk members along said shaft for releasing said printing hammer against said type wheel.

31. In a receiver device, a plurality of notched selector disks, a type wheel comprising a plurality of type characters, a printing hammer normally urged toward said type bars, means responsive to received impulses for sliding said disk members longitudinally along said shaft, and means responsive to a predetermined setting of said selector bars for releasing said hammer to print a selected character.

32. In a receiver device, a plurality of notched selector disks, each of said disks having a plurality of positions along the axis of said shaft, a type wheel, a rotating shaft for supporting said disks and said type wheel, means responsive to received impulses for moving said disks longitudinally along said shaft, and means operative at a position in the rotation of said shaft which is determined by the setting of said selector disks longitudinally along said shaft for selectively printing characters of said type wheel.

33. In a printing telegraph receiver, a shaft, a type wheel, a plurality of selectors, each operable to a plurality of positions longitudinally along said shaft, means for rotating said shaft, means for selectively positioning said selectors as said shaft rotates, a printing hammer normally urged towards said type wheel, means for locking said hammer from movement against the type wheel, and means operative in accordance to the positions of said selectors along said shaft for releasing said hammer at a predetermined position in the rotation of said type wheel.

34. In a receiver device, a plurality of selector bars, a plurality of setting forks indi-

vidual to said selector bars, a plurality of notched disk members, each of said disk members being provided with cam members, a rotating shaft for supporting said disk members, means responsive to received impulses for selectively operating said selector bars, said selector bars being provided with extensions which co-act with their associated setting forks, whereby said forks are selectively operated in accordance with movement of said selector bars, said setting forks being arranged to engage the cams of their associated selector disks as said disks rotate for selectively moving said disks longitudinally along said rotating shaft in accordance with the positioning of said selector bars, a type wheel comprising a plurality of type characters, a plurality of seeker members, a printing hammer normally locked against operation, means whereby said seeker members are selected for operation in accordance with the positioning of said disk members, means whereby said seeker members are operated when said shaft has assumed a predetermined position, and means controlled by said seeker for releasing said locked hammer whereby said printing hammer is released for operation.

35. In a receiver, a type wheel comprising a plurality of rows of type characters, a plurality of type hammers one for each of said rows, said hammers being normally urged toward said characters, latching devices individual to each of said hammers for normally latching said hammer, means for selectively positioning said type characters before said hammers and for operating one of said latching members whereby a predetermined one of said hammers is released to print a type character, said means comprising a plurality of selectors, a shaft for supporting said type wheel and said selectors, and means for moving said selectors transversely with respect to said shaft for selecting one of said characters for operation.

36. In a receiver, a type wheel comprising a plurality of groups of type characters, a printing hammer individual to each of said groups, a plurality of notched selector disks, a shaft for supporting said type wheel and said disks, means for selectively operating said disks for selecting one of said type characters for operation, and means responsive to the positioning of said disks for selecting one of said printing hammers whereby a predetermined character is printed.

37. In a printing telegraph receiver, a type wheel, a printing hammer, a tape arranged to move between said type characters and said printing hammer, a cam shaped disk, a shaft supporting said type wheel and said cam shaped disk and a cam roller carrying said tape and arranged to follow said cam shaped disk for moving said tape at a predetermined position of said shaft.

38. In a printing telegraph receiver, a type wheel, a cam shaped disk, a rotating shaft for carrying said type wheel and said disk, a cam roller, a spacing latch controlled by said cam roller, and a pawl arranged to move said spacing latch as said cam roller passes over a portion of said cam.

39. In a printing telegraph receiver, a selector device responsive to received line current impulses, means following each operation of said selective device in response to a line current impulse for rendering it unresponsive to further impulses for a predetermined interval, a plurality of notched concentric selector disks, means controlled by the positioning of said selectors for selectively spacing said disks from each other, and a type wheel selectively controlled in accordance with the positioning of said selector disks.

40. In a printing telegraph receiver, a plurality of selector members, a plurality of operating members individual to said selector members, said operating members being successively associated with their individual selector members, means for preventing said operative members from being responsive to said line current impulses before being properly positioned, a shaft, a plurality of notched selector disks mounted on said shaft, means controlled by the positioning of said selectors for selectively spacing said disks from each other, and a type wheel selectively controlled in accordance with the positioning of said selector disks.

41. In a printing telegraph receiver, a plurality of selector mechanisms, a plurality of operating members individual to said selector members, said operating members being successively associated with their individual selector members, means for preventing said operative members from being responsive to said line current impulses before being properly positioned, a shaft, a plurality of notched selector disks mounted on said shaft, means controlled by the positioning of said selectors for selectively spacing said disks from each other, and a type wheel selectively controlled in accordance with the positioning of said selector disks.

42. In a printing telegraph receiver, a plurality of selector members, a plurality of latch members, individual thereto, a rotating shaft comprising a plurality of cams individual thereto, a rotating shaft comprising a plurality of cams individual to said selector members, means for rotating said shaft whereby said cam members operate said latch members sequentially, means responsive to received impulses for moving said shaft longitudinally whereby said cam members operate said selector members, means whereby said latch members latch said operated selector members, a second shaft, a plurality of notched selector disks mounted on said shaft,

means controlled by the positions of said selectors for selectively spacing said disks from each other, and a type wheel selectively controlled in accordance with the positioning of said selector disks.

43. In a printing telegraph receiver, a plurality of selector members, a plurality of latch members, a rotating shaft comprising a plurality of cam members individual to said selector members, said selector members and said latch members being longitudinally spaced from each other with respect to said shaft, means responsive to line current impulses for moving said shaft for operating said selector members or said latch members in accordance with the longitudinal movement of said shaft, a plurality of notched selector disks, means controlled by the positions of said selectors for selectively spacing said disks from each other, and a type wheel selectively controlled in accordance with the positioning of said selector disks.

44. In a printing telegraph receiver, a plurality of selector members, a plurality of latch members individual to said selector members and operative means responsive to received current for selectively operating either said selector members or their individual latch members in accordance with received impulses, a plurality of notched selector disks, means controlled by the positioning of said selectors for selectively spacing said disks from each other, and a type wheel selectively controlled in accordance with the positioning of said selector disks.

45. In a printing telegraph receiver, a plurality of selector devices, means for moving each of said selector devices to either of two positions in response to received line current impulses and means following each operation of each said devices for locking it in its assumed position for a predetermined length of time, a plurality of notched disks, a type wheel, a shaft for supporting said disks and said type wheel, means responsive to said selectors for moving said notched disks longitudinally with respect to said shaft in accordance with the operation of said selectors, a latch printing hammer and means operative in accordance with the positioning of said latched disks for releasing said printing hammer for operation against a predetermined one of said type characters.

46. In a printing telegraph receiver, a rotating shaft comprising a plurality of cam members spaced about the periphery of said shaft, means for rotating said shaft for successively bringing said cam members into operative positions, means responsive to line current impulses for operating said shaft as each of said members is brought into said operative position, means for rendering said shaft unresponsive to line current impulses while said cam members are positioned intermediate said operative position, a plurality of notched

disks, a type wheel, means controlled by said cam members for moving said notched disks longitudinally with respect to said shaft, a latched printing hammer and means operative in accordance with the positioning of said latched disks for releasing said printing hammer for operation against a predetermined one of said type characters.

47. In a printing telegraph receiver, selector members, a shaft comprising a plurality of cam members, one for each of said cam members, means whereby said cam members are successively brought into engagement with their individual selector members, means responsive to line current impulses for successively operating said cam members as they engage their individual selector members whereby said selector members are positioned in response to received impulses, means operative following each operation for locking each of said cam members to complete its operation, a plurality of notched disks, a type wheel, a shaft for supporting said disks and said type wheel, means responsive to said selectors for moving said notched disks longitudinally with respect to said shaft in accordance with the operation of said selectors, a latched printing hammer and means operative in accordance with the positioning of said latched disks for releasing said printing hammer for operation against a predetermined one of said type characters.

48. In a printing telegraph receiver, a plurality of selector members, a plurality of latch members, a rotating shaft, said shaft being movable longitudinally in response to received impulses, a plurality of cam members integral with said shaft on its periphery for selectively operating said selector members or said latch members in accordance with its longitudinal position, a plurality of notched disks, a type wheel, a shaft for supporting said disks and said type wheel, means responsive to said selectors for moving said notched disks longitudinally with respect to said shaft in accordance with the operation of said selectors, a latched printing hammer and means operative in accordance with the positioning of said latched disks for releasing said printing hammer for operation against a predetermined one of said type characters.

49. In a printing telegraph receiver, a plurality of operating members, a plurality of selector and latch members individual to each of said operating members, means responsive to the received impulses whereby each of said cam members operates its individual selector, means including selector levers individual to said cam members whereby said latch members are locked from further operation following each operation, a plurality of notched disks, a type wheel, a shaft for supporting said disks and said type wheel, means responsive to said selectors for moving said notched disks longitudinally with respect to said shaft

in accordance with the operation of said selectors, a latched printing hammer and means operative in accordance with the positioning of said latched disks for releasing said printing hammer for operation against a predetermined one of said type characters.

50. In a printing telegraph receiver, a plurality of selector members, a plurality of point selectors individual to said selector members and positioned adjacent thereto, a rotating shaft comprising a plurality of cam members positioned about said shaft for selectively operating said selectors, said selector members or point selectors being in the path 10 of their individual cam members where said cam members are locked to complete each operation, a plurality of notched disks, a type wheel, a shaft for supporting said disks and said type wheel, means responsive to said 15 selectors for moving said notched disks longitudinally with respect to said shaft in accordance with the operation of said selectors, a latched printing hammer and means operative in accordance with the positioning of said 20 disks for releasing said printing hammer for operation against a predetermined one of said type characters.

51. In a printing telegraph receiver, a plurality of selector members, a rotating shaft, a plurality of cam members individual to said selector members integral with and positioned around said shaft, said shaft being rotatable for sequentially positioning each of said cam members adjacent its associated selector member, means responsive to received line current impulses for selectively operating said selector members in their operate position, a plurality of notched disks, a type wheel, a shaft for supporting said selectors and said 35 type wheel, means responsive to said selectors for moving said notched disks longitudinally with respect to said shaft in accordance with the positioning of said latched disks for releasing said printing hammer for operation 40 against a predetermined one of said type characters.

52. In a receiver, a rotating device operative in response to impulses of a predetermined rate of reception, means operative 50 should said rate of reception increase for automatically preventing said device from operating at said higher rate, a type wheel comprising a plurality of groups of type characters, a printing hammer individual to each of said groups and means responsive to the operation of said selectors for selectively positioning one of said type characters opposite each of said hammers and for selectively releasing a predetermined one of said type 55 hammers.

53. In a printing telegraph receiver, a plurality of selecting members, a rotating shaft, a plurality of cams individual to said selector members, said cams being integral with and 60 about said shaft whereby each of said cams is

positioned opposite its individual selector members in succession, means responsive to line current impulses for moving said shaft longitudinally in response to received impulses whereby each cam member operates its individual selector, means operative following the operation of each cam for locking said shaft from further operation until the succeeding cam is in a position to operate its associated selector, a type wheel comprising a plurality of groups of type characters, a printing hammer individual to each of said groups and means responsive to the operation of said 70 selectors for selectively positioning one of said type characters opposite each of said hammers and for selectively releasing a predetermined one of said type hammers.

54. In a printing telegraph receiver, a plurality of selector members, a plurality of latch members individual to said selector members, means operating in accordance with received line current impulses for operating either said 75 latch members or said selector members, a type wheel comprising a plurality of groups of type characters, a printing hammer individual to each of said groups and means responsive to the operation of said selectors for selectively positioning one of said type characters opposite each of said hammers and for selectively releasing a predetermined one of said type 80 hammers.

55. In a printing telegraph receiver, a plurality of selector members, a plurality of latch members individual to said selector members, a rotating shaft comprising a pair of cam 100 members, said cam members being arranged to be sequentially positioned opposite their individual selectors and latch members, means responsive to received impulses for operating said shaft longitudinally whereby 105 said cam members operate said selectors or said latch members in accordance with the impulses, a type wheel comprising a plurality of groups of type characters, a printing hammer individual to each of said groups and means responsive to the operation of said 110 selectors for selectively positioning one of said type characters opposite each of said hammers and for selectively releasing a predetermined one of said type hammers.

56. In a printing telegraph receiver, a plurality of selector members, a latch member individual to said selector member and a point selector member individual to each of said selector members, a rotating shaft, a plurality of cam members arranged about said shaft, means for moving said shaft longitudinally in response to received impulses, said selector members being arranged to be operated by their individual cam members in 115 accordance with the longitudinal movement of said shaft, said selector member and said individual point selector member being arranged to lock their individual cam members in accordance with the operation of said 120 selector members.

cam, a type wheel comprising a plurality of groups of type characters, a printing hammer individual to each of said groups and means responsive to the operation of said selectors for selectively positioning one of said type characters opposite each of said hammers and for selectively releasing a predetermined one of said type hammers.

57. In a printing telegraph receiver, a shaft normally latched against rotation, means for rotating said shaft, said shaft being normally latched against rotation, means responsive to received impulses for latching said shaft whereby it is rotated, a second shaft, a type wheel carried by said second shaft, said energy supplying means also tend to rotate said second shaft, a latch device for preventing said shaft from rotating, and means operative following the complete rotation of said first mentioned shaft for unlatching said second shaft whereby it is permitted to make one complete revolution.

58. In a printing telegraph receiver, a first shaft, a second shaft, a common source of energy for rotating said shafts, said shafts normally being latched against rotation, means responsive to line current impulses for unlatching said first shaft, said means also operating said first shaft selectively in response to received impulses, selector disks carried by said second shaft, means following a complete rotation of said first shaft for unlatching said second shaft for rotation and selector members selectively controlled by the movement of said first shaft in response to received impulses for selectively positioning said selector disks.

59. In a printing telegraph receiver, a first shaft, a second shaft, said shafts being normally latched against rotation, a common rotating means for said shafts, means responsive to a received impulse for unlatching said first shaft, and for selectively moving said shaft longitudinally as it rotates in response to received impulses, selector members latched in predetermined positions in accordance with the longitudinal movement of said shaft, means following the rotation of said shaft for unlatching said second shaft, a plurality of selector disks carried by said second shaft, each of said disks being individual to one of said selector members and means operative as said second shaft rotates for simultaneously positioning said selector disks in accordance with the operation of said selector bars.

60. In a printing telegraph receiver, a first shaft, a second shaft, said shafts being normally latched against rotation, a common rotating means for said shafts, means responsive to a received impulse for unlatching said first shaft, and for selectively moving said shaft longitudinally as it rotates in response to received impulses, selector members latched in predetermined positions in accord-

ance with the longitudinal movement of said shaft, means following the rotation of said shaft for unlatching said second shaft, a plurality of selector disks carried by said second shaft, each of said disks being individual to one of said selector members, means operative as said second shaft rotates for simultaneously positioning said selector disks in accordance with the operation of said selector bars, a type wheel carried by said second shaft and means for selectively printing a predetermined one of said type characters in accordance with the selected positioning of said selector disks.

61. In a printing telegraph receiver, a plurality of first selectors, means for variably operating said selectors in accordance with received code combinations of impulse conditions, a second set of selectors, means for operating said second selectors in accordance with the operation of said first selectors, a plurality of type characters in normal and shift positions, means controlled by said second selectors for selecting a type character in normal and shift position, an additional selector associated with said first selectors and variably operated by said first mentioned means in accordance with an impulse condition following said code combination and means directly controlled by said additional selector for selecting between the selected characters in normal and shift position.

62. In a printing telegraph receiver, a plurality of first selectors, means for variably operating said selectors in accordance with received code combinations of impulse conditions, a second set of selectors, means for operating said second selectors in accordance with the operation of said first selectors, a plurality of type characters in normal and shift position, means controlled by said second selectors for selecting type characters in normal and shift position, an additional selector associated with said first selectors and variably operated in accordance with an impulse condition following said code combination and means directly controlled by said additional selector for selecting between the selected characters in normal and shift position.

63. In a printing telegraph receiver, a plurality of first selectors, means for variably operating said selectors in accordance with received code combinations of impulse conditions, a second set of selectors, means for operating said second selectors in accordance with the operation of said first selectors, a plurality of rows of type wheel characters, means controlled by said second selectors for selecting a type character in each row of type wheel characters, an additional selector associated with said first selectors and variably operated in accordance with an impulse condition following said code combination and means directly controlled by said additional selector for selecting between the selected characters in normal and shift position.

selector for selecting one of said rows of type-wheel characters for operation.

64. In a printing telegraph receiver, a plurality of first selectors, means for variably operating said selectors in accordance with received code combinations of impulse conditions, a second set of selectors, means for operating said second selectors in accordance with the operation of said first selectors, a plurality of rows of typebar characters, means controlled by said second selectors for selecting a character in each of said rows for printing, a printing hammer for each row of characters, and an additional selector associated with said first selectors and operated in accordance with an impulse condition following said code combinations for directly operating one of said printing hammers against its associated row of characters.
65. In a printing telegraph receiver, a plurality of first selectors, means for variably operating said selectors in accordance with received code combinations of impulse conditions, a second set of selectors, means for operating said second selectors in accordance with the operation of said first selectors, a plurality of rows of typebar characters, means controlled by said second selectors for selecting a character in each of said rows for printing, a printing hammer for each row of characters normally latched against operation and an additional selector associated with said first selectors and operated in accordance with an impulse condition following said code combination for directly releasing one of said printing hammers against its associated row of characters.

66. In a printing telegraph receiver, a plurality of typewheel characters, a printing hammer for each typewheel, a plurality of selectors, means responsive to received code combinations of impulse conditions for variably operating said selectors, means controlled by said selectors for selecting a character on each of said typewheel rows for operation and a selector associated with said plurality of selectors and controlled by an impulse following said code combination for selecting one of said typewheel rows for operation.

67. In a printing telegraph receiver, a selector, a rotating device, a magnet energized in accordance with received code combinations of impulse conditions for selectively operating said rotating device, one direction of current flowing through said magnet acting to operate the rotating device in one direction and the opposite direction of current flowing through said magnet acting to operate the rotating device in the opposite direction and means operative for rendering said magnet ineffective to operate said rotating device while said rotating device is in a position intermediate said predetermined position.

68. In a printing telegraph receiver, a rotating shaft, a magnet responsive to current flowing therethrough in one direction for operating said shaft longitudinally in one direction and responsive to current flowing therethrough in the opposite direction for moving said shaft longitudinally in the opposite direction and means for locking said shaft from said longitudinal movement at predetermined points in the path of said rotating shaft.

69. In a printing telegraph receiver, a plurality of selector members, a rotating shaft operated in accordance with received code combinations of impulse conditions, a plurality of cam members individual to said selector members integral with and positioned around said shaft, said shaft being rotatable for sequentially positioning each of said cam members adjacent to its associated selector member, means for latching said selector members in position until released by a change of impulses in the succeeding cycle of operations, a plurality of rows of type-wheel characters, means controlled by said selector members for selecting a character in each row for printing and a further selector associated and operated in accordance with an impulse following each code combination for selecting the row in which the character to be printed is located.

70. In a receiver device, a plurality of selector bars, a plurality of setting forks individual to said selector bars, a plurality of notched disk members, each of said disk members being provided with cam members, a rotating shaft for supporting said disk members, means responsive to received impulses for selectively operating said selector bars, said selector bars being provided with extensions which co-act with their associated setting forks, whereby said forks are selectively operated in accordance with movement of said selector bars, said setting forks being arranged to engage the cams of their associated selector disks as said disks rotate for selectively moving said disks longitudinally along said rotating shaft in accordance with the positioning of said selector bars, a type wheel comprising a plurality of rows of type characters, a plurality of seeker members, a printing hammer for each row normally locked against operation, means whereby said seeker members are selected for operation in accordance with the positioning of said disk members, means whereby said seeker members are operated when said shaft has assumed a predetermined position and means operated in response to an impulse following said code for selectively releasing one of said locked hammers whereby said printing hammer is released for operation.

71. In a receiver, a type wheel comprising a plurality of rows of type characters, a plurality of type hammers one for each of said

- rows, said hammers being normally urged toward said characters, latching devices individual to each of said hammers for normally latching said hammer, means responsive to code combinations of impulse conditions for selectively positioning said type characters before said hammers, means responsive to an impulse condition following said code combinations for operating one of 5 said latching members whereby a predetermined one of said hammers is released to print a type character, said means comprising a plurality of selectors, a shaft for supporting said type wheel and said selectors, 10 and means for moving said selectors transversely with respect to said shaft for selecting one of said characters for operation. 15
72. In a printing telegraph receiver, a plurality of selector members, a plurality of latch members individual thereto, a rotating shaft comprising a plurality of cams individual thereto, a rotating shaft comprising a plurality of cams individual to said selector members, means for rotating said shaft 20 whereby said cam members operate said latch members sequentially, means responsive to received impulses for moving said shaft longitudinally whereby said cam members operate said selector members, means where- 25 by said latch members latch said operated selector members, a second shaft, a plurality of notched selector disks mounted on said shaft, a plurality of rows of type characters, means controlled by selector disks for select- 30 ing a character in each row, a printing ham- 35 mer for each row and means controlled by an impulse following said impulses for selectively operating one of said printing ham- 40 mers.
73. In a printing telegraph receiver, a plurality of selector members, a plurality of latch members, a rotating shaft comprising a plurality of latch members, a rotating shaft 45 comprising a plurality of cam members individual to said selector members, said selector members and said latch members being longitudinally spaced from each other with respect to said shaft, means responsive to line current impulses for moving said shaft 50 for operating said selector members or said latch members in accordance with the longitudinal movement of said shaft, a plurality of notched selector disks, a plurality of rows 55 of type characters, means controlled by selector disks for selecting a character in each row, a printing hammer for each row and means controlled by an impulse following said impulses for selectively operating one of said printing hammers. 60
74. In a printing telegraph receiver, a plurality of selector devices, means for moving each of said selector devices to either of two positions in response to received code combinations of impulse conditions, means 65 following each operation of each of said de- 70 vices for locking it in its assumed position for a predetermined length of time, a plurality of notched disks, a plurality of rows of typewheel characters, a shaft for supporting said disks and said typewheel, means responsive to said selectors for moving said notched disks longitudinally with respect to said shaft in accordance with the operation of said selectors, means controlled by said disks for selecting a character in each row 75 for operation, a latched printing hammer for each typewheel row and means operative in accordance with an impulse condition following said code combination for releasing said printing hammer for operation against a predetermined one of said type characters. 80
75. In a selector mechanism, a plurality of selector members; a shaft comprising a plurality of cam members one for each of said selector members; means whereby said cam members are successively brought into operative relation with their individual selector members; means for causing said cam members to engage their individual selector members in response to received signalling conditions; and means individual to each selector member for locking each of said cam members to compel completion of its operation on its individual selector member in response to the received signalling conditions. 85
76. In a selector mechanism, a plurality of selector members; a plurality of latch members individual to said selector members; a rotating shaft; a plurality of cam members integral with said shaft and individual to 90 said selector members; means responsive to received current conditions for moving said shaft longitudinally to position said cam members to operate their individual selectors or latch members; and a plurality of mem- 95 bers positioned to lock said shaft against longitudinal movement following each operation. 100
77. In a selector mechanism, selector members, and means movable in a plurality of directions in response to code combinations of selecting conditions for selectively setting said selector members; said selector members remaining set in any given position until a different position thereof is required in a 110 succeeding cycle of operations. 115
78. In a selector mechanism, a plurality of selector members; a selector setting member movable in a plurality of directions to selectively set said members; means responsive to code combinations of selecting conditions for variably actuating said selector setting member, and means for latching said selector members in set position until a different position thereof is required in a succeeding cycle 120 of operations. 125
79. In a selector mechanism, a plurality of selector members; a plurality of cam members individual to said selector members; means responsive to code combinations of se- 130

lecting conditions for actuating said cam members to set said selector members; and means for latching said selector members in set position until a different position thereof is required in a succeeding cycle of operations.

80. In a register, a set of first selectors; means for variably operating said selectors in accordance with received code combinations of signalling conditions; a second set of selectors; means for operating said second selectors in accordance with the operation of said first selectors; a plurality of groups of characters on said register; means controlled by said second selectors for selecting a character in each group; an additional selector associated with said first selector and variably operated by said first mentioned means in accordance with a signalling condition added to each code combination; and means directly controlled by said additional selector for effecting registration of one of the selected characters.

81. In a register, a plurality of first selectors; means for variably operating said selectors in accordance with received code combinations of signalling conditions; a second set of selectors; means for operating said second selectors in accordance with the operation of said first selectors; a plurality of characters arranged in groups; means controlled by said second selectors for selecting a character in each group; an additional selector associated with said first selector and variably operated in accordance with a signalling condition added to each code combination; and means directly controlled by said additional selector for effecting registration of one of the selected characters in said groups.

82. In a selector mechanism, a rotating device; a polarized magnet energized in accordance with received code combinations of impulse conditions of current reversals for selectively positioning said rotating device in one of two predetermined positions; and means operative for rendering said magnet ineffective to operate for a predetermined interval said rotating device, while said rotating device is in either of said predetermined positions.

83. In a register, a plurality of selector members, a rotating shaft operated in accordance with received code combinations of signalling conditions; a plurality of cam members individual to said selector members positioned around said shaft, said shaft being rotatable for sequentially positioning each of said cam members adjacent to its associated selector member; means for latching said selector members in position until released by a change of its controlling condition in the succeeding cycle of operations; a plurality of rows of characters; means controlled by said selector members for simultaneously selecting a character in each row;

and a further selector operated in accordance with a signalling condition following each code combination for selecting the row in which the character to be registered is located.

84. In a printing telegraph receiver; a first set of selectors responsive to received code combinations of signalling conditions; a second set of selectors; transfer mechanism operative following the setting of said first selectors for transferring the setting of said first selectors to said second selectors; a plurality of printing hammers; operating mechanism therefor connected to a selector of said first set of selectors for conditioning one of said hammers for operation simultaneously with the transfer of the setting of said first set of selectors to said second selectors; and a type wheel selectively operated in accordance with the setting of said second set of selectors to condition a character for printing.

85. In a printing telegraph receiver; a plurality of characters; a first set of selectors; a second set of selectors; a source of mechanical power for setting said first set of selectors in accordance with received code combinations of signalling conditions; means for transferring the setting of said first set of selectors to said second selectors; a plurality of printing hammers; control means for said printing hammers in operative relation with one of said first set of selectors and directly operated thereby in accordance with one signalling condition of a code combination for conditioning one of said printing hammers for operation; and means controlled by said second selectors for selecting one of said characters for printing operation by said conditioned hammer.

86. In a printing telegraph receiver; a first set of selectors selectively set responsive to received code combinations of signalling conditions; a second set of selectors; transfer mechanism operative following the setting of said first selectors for transferring the settings thereof to said second set of selectors; printing apparatus variably conditioned for printing operations in accordance with the setting of said second set of selectors; a plurality of type hammers; controlling means for said printing hammers and a selector operated in response to a signalling condition in addition to said code combination of conditions, said selector being directly connected to and variably operating said controlling means to condition one or the other of said printing hammers for operation in accordance with the setting of said selector.

87. In a telegraph receiver; a typewheel structure provided with a plurality of groups of characters and having a normal position of rest; a first set of selectors responsive to received code combinations of signal-

ling conditions; a second set of selectors operated by said first selectors for selecting a character in each of said groups for printing; means for initiating rotation of said type wheel structure from normal rest position after receipt of a code combination, printing mechanism for said type wheel structure; and means for selectively operating said printing mechanism to effect printing of a selected character from one of said groups while said type wheel structure is rotating.

88. In a telegraph receiver; a typewheel structure comprising a plurality of groups of characters; a first set of selectors responsive to received code combinations of signalling conditions; a second set of selectors simultaneously operated by said first set of selectors for selecting a character in each of said groups; printing mechanism; a record tape; and means for operating said printing mechanism to effect printing of selected characters from said groups in relatively offset relation with respect to each other.

89. In a telegraph receiver; a typewheel structure comprising a plurality of groups of characters and having a normal position of rest; printing mechanism; a first set of selectors responsive to a received code combination of signalling conditions; a second set of selectors controlled by said first selectors for selecting a character in each of said groups; means for causing said type wheel structure to rotate through one revolution after the receipt of a code combination; and means for printing a selected character from only one of said groups while said type wheel structure is in rotation.

90. In a telegraph receiver; a type wheel structure comprising a plurality of groups of characters; a plurality of printing means for said type wheel structure; a first set of selectors responsive to received code combinations of signalling conditions; a second set of selectors simultaneously controlled by said first selectors for simultaneously selecting a character in each group; and means for selectively printing a character from one or the other of said groups.

91. In a telegraph receiver; a plurality of groups of characters; printing means; a first set of selectors responsive to a received code combination of signalling conditions; a second set of selectors simultaneously controlled by said first selectors for selecting a character in each of said groups; printing means; and means responsive to a condition accompanying each code combination of signalling conditions operative to cause said printing means to selectively print the selected characters from said groups in offset relation with respect to each other.

In testimony whereof I affix my signature.

EDWARD E. KLEINSCHMIDT.
